Primary Examiner — Mitchell I. Siegel(74) Attorney, Agent, or Firm — Dunlap Bennett & Ludwig PLLC(57) CLAIM

The ornamental design for a golf club stand, as shown and described.

DESCRIPTION

FIG. 1 is a perspective view of a golf club stand;

FIG. 2 is a front elevation view thereof;

FIG. 3 is a left side elevation view thereof;

FIG. 4 is a rear side elevation view thereof;

FIG. 5 is a right side elevation view thereof;

FIG. 6 is a top plan view thereof; and,

FIG. 7 is a bottom plan view thereof.

The broken lines shown in the drawings depict a cap that form no part of the claimed invention.
